United States Patent Office

Des. 208,476
Patented Sept. 5, 1967

208,476

COIN OPERATED TELEPHONE OR SIMILAR ARTICLE

Louis P. La Barge, Newport Beach, Calif., assignor, by
mesne assignments, to Zero Manufacturing Co., Bur-
bank, Calif., a corporation of California

Filed Aug. 13, 1964, Ser. No. 81,267

Term of patent 14 years

(Cl. D26—14)

FIGURE 1 is a perspective view looking from the top and right-hand side of a coin operated telephone or similar article showing my new design, with the receiver off of the hook; and

FIGURE 2 is a perspective view looking from the bottom and left-hand side, with the receiver on the hook.

The back, not shown, is a substantially flat unornamented surface.

I claim:

The ornamental design for a coin operated telephone or similar article, as shown and described.
